UNITED STATES PATENT OFFICE

161,342

EXPANSIBLE BRACELET OR THE LIKE

Max Jacoby, Lawrence, N. Y., assignor to Jacoby-Bender, Inc., New York, N. Y., a corporation of New York

Application June 1, 1949, Serial No. 2,987

Term of patent 7 years

(Cl. D45—4)

To all whom it may concern:

Be it known that I, Max Jacoby, a citizen of the United States and a resident of Lawrence, Long Island, county of Nassau and State of New York, have invented a new, original, and ornamental Design for an Expansible Bracelet or the like, of which the following is a specification, reference being had to the accompanying drawing, forming a part thereof, in which:

Fig. 1 is a top plan view of an expansible bracelet embodying my new design, the conventional connecting links being shown in broken lines;

Fig. 2 is a top plan view of the bracelet with the connecting links omitted, the conventional bottom links visible between the expanded top links being illustrated in broken lines;

Figs. 3 and 4 are enlarged end and side elevational views, respectively, of the symmetrical center link; and

Figs. 5 and 6 are enlarged left and right-hand side elevational views respectively, of one of the right-hand heart shaped links.

I claim:

The ornamental design for an expansible bracelet or the like, as shown and described.

MAX JACOBY.
